UNITED STATES PATENT OFFICE.

JOHN H. GIBSON, OF BRUIN, PENNSYLVANIA.

WINDOW-SASH HOLDER.

1,346,449.

Specification of Letters Patent. Patented July 13, 1920.

Application filed July 24, 1919. Serial No. 313,027.

To all whom it may concern:

Be it known that I, JOHN H. GIBSON, a citizen of the United States, residing at Bruin, in the county of Butler and State of Pennsylvania, have invented a new and useful Window-Sash Holder, of which the following is a specification.

The present invention relates to window sash holders the object being to provide a window sash holder which is used in connection with a sliding sash and which will retain the same in any adjusted position.

A second object of the invention is to provide a window sash holder which will effectively retain the sash in raised position and which will at the same time prevent rattling of the sash.

A further general object of the invention is to provide a sash holder which is applicable to any vertically movable sash and which will dispense with weights, pulleys and cords that are now commonly used.

It is another important object to provide a window sash holder which includes a spring urged housing in which is journaled a roller for engagement with the window frame to retain the window sash in adjusted position, and means associated with the roller and housing to prevent the roller from rotating in a counter-clockwise direction upon the lowering of the sash.

Still another object of the invention resides in the provision of a spring actuated roller which frictionally engages the side rail of the window frame to retain the sash in adjusted position, a novel mounting being provided for the roller which not only serves as a mounting for the roller but as an abutment for the spring used in the construction of the device.

An additional general object of the invention resides in the provision of a sash holder having the above characteristics, which is simple in construction, which consists of few parts and which may be manufactured and placed on the market at a minimum cost.

With the above and other objects and advantages in mind, the invention consists of the combinations of elements, constructions and formations, arrangement of parts, and general assemblage, the details of which will be hereinafter enlarged upon and recited in the appended claim, one embodiment of the

invention being illustrated in the accompanying drawings, wherein:

Figure 1 is a sectional view of a window sash having my improved sash holder mounted therein, parts being broken away;

Fig. 2 is a fragmentary sectional view of one of the side bars of a window frame and sash showing the sash holder associated therewith;

Fig. 3 is a fragmentary end elevation of the sash and showing the sash fastener in end elevation; and

Fig. 4 is a longitudinal vertical sectional view of the sash fastener removed.

Referring in detail to the drawings, the numeral 5 designates the vertically movable sash while 6 designates one of the side rails of the same, the inner face of the side rail of the sash 5 being provided with a rectangular recess 7. A cylindrical recess 8 is also provided in this rail 6 rearwardly of the recess 7. The opposed vertical faces of the side walls of the recess 7 are provided with parallel longitudinal grooves 10.

Adapted for longitudinal movement in the recess 7 and insertibly accommodated therein is a substantially rectangular housing or plunger 11 which is open at one side to receive a roller 12 mounted upon a shaft 13 in the side walls of the casing 11, the ends of the shaft being slidably engaged in the longitudinal grooves 10. The rear end of the housing 11 is formed with a thickened part, the inner surface of which is curved longitudinally, as indicated at 13'. One or more rollers 14 are positioned on this inner curved surface and are adapted to bind against the roller 12 and the rear end of this curved wall should the roller start to rotate in a counter-clockwise direction. The rear face of the casing 11 is formed with a rearwardly extending projection 14'. A disk 15 having a central aperture is mounted upon a screw 15', which is secured in and extends rearwardly of the projection 14'. This screw is equipped at its free end with an enlarged end 17, which at times abuts with the bottom of the recess in the sash rail and prevents undue inward movement of the housing 11. A coil spring 16 encircles the projection 14 and bears against the disk and normally urges the same toward the head 17. The disk 15 normally bears against the bottom of the circular recess in the rail 5.

The coil spring 16 bears against the casing and normally urges the same to a position where the roller engages the side bar of the window frame, the disk 15 being held 5 against the bottom of the recess 8 by the opposite end of the coil spring.

The embodiment of the invention herein shown and described is considered the preferred form, but it is to be understood that 10 the same is susceptible to various modifications, and that my limits of such modification are governed only by what is claimed.

What is claimed is:—

15 In a sash fastener, a vertically movable sash having a recess in one side thereof, a housing slideable in the recess, the rear wall and the bottom wall of the housing being

formed with a thickened part, the surface of which being longitudinally curved, a roller journaled in the housing and movable over 20 one rail of the window frame, rollers movable over the curved surface and adapted to bind against the first-mentioned roller to lock the same against rotation upon the lowering of the sash, and expansible means 25 urging the housing toward the sash frame.

In testimony that I claim the foregoing as my own, I have hereto affixed my signature in the presence of two witnesses.

JOHN H. GIBSON.
